UNITED STATES PATENT OFFICE.

EDWARD JACKSON YORK, OF HOUSTON, TEXAS.

CONTAINER.

1,188,129.

Specification of Letters Patent. Patented June 20, 1916.

Application filed April 17, 1915. Serial No. 22,007.

To all whom it may concern:

Be it known that I, EDWARD JACKSON YORK, a citizen of the United States, and a resident of Houston, in the county of Harris and State of Texas, have invented a new and Improved Container, of which the following is a full, clear, and exact description.

My invention relates to containers, such as crates, barrels and other members adapted for containing merchandise, fruits, vegetables and the like.

More particularly stated, my invention comprehends a container adapted to be made up in so-called collapsed form and to receive its final shape after a comparatively small expenditure of labor and work, its final shape being suitable for the ultimate use of the article, considered as a container.

My invention further comprehends a container comprising a number of staves secured at their ends and flexible strips of sheet metal, the latter being adapted to be bent in a direction crossing their general length, and the portion thus bent suitable to form a limiting stop for alining the ends of the staves and preventing relative displacement of the same.

Reference is made to the accompanying drawings, forming a part of this application and in which like letters indicate like parts.

Figure 1 is a perspective showing my improved container, while being made up as a barrel and also showing various auxiliary parts used in conferring upon the barrel its proper shape; Fig. 2 is a perspective showing the barrel complete; Fig. 3 is a substantially central longitudinal section through the mechanism appearing in Fig. 1; Fig. 4 is a plan view of the form of the container appearing in Figs. 1, 2 and 3, but showing the same in its initial or collapsed condition; and Fig. 5 is an end view partly in elevation and partly in section, showing another form of my container, which in this instance is made up into a crate with flattened sides.

The general form of the container as originally made up, is shown more particularly in Fig. 4. A number of staves 6 which are of uniform cross section, or in other words, are free from bilge, are disposed edge to edge and their ends brought into alinement. Two strips 7 of sheet metal, preferably steel or iron, are laid across the ends of the staves and so disposed that por-

tions 8 of these strips slightly overhang the adjacent ends of the staves. The strips 7 are provided with integral portions 9 having facets 10. By means of nails 11 or other appropriate fastenings, the strips 7 are secured to the adjacent end portions of the staves. At 12 are head boards made somewhat like the end pieces of any other barrel.

The device thus completed constitutes the container as ready for shipment in large quantities or for handling in bulk. In this form, the container occupies practically no more room than would be necessarily occupied by the staves and strips, no matter in what form the same may be arranged. While in this form, the containers may be grouped together and made up into a bale or package containing any convenient number and such bales or packages may be shipped and otherwise handled at a minimum of cost.

For convenience in assembling the various parts of this form of container, I employ a pair of massive hoops 13, provided with ends 14, adapted to be brought close together. These massive hoops 13, because of their use, I designate as reducing bands. The container, shown in Fig. 4, is bent round, substantially into cylindrical form, so that the projecting portions 9 of the strips 7, slightly overlap the opposite end portions of these strips, as may be understood from Fig. 1. This done, the reducing bands 13 are slipped over the ends of the container. A number of mandrel bars 15, each having its middle portion wider than its end portions, as indicated in Fig. 1, are spaced substantially equi-distant and in engagement with the reducing bands 13. Two hoops 16 of large diameter are next slipped over the ends of the mandrel bars and driven, by hammering or otherwise, so as to grip upon the comparatively thick or wide portions of the mandrel bars. The mandrel bars thus exert pressure upon the reducing bands 13 and in doing this, they form the container in the shape of a barrel, which, however, has no bilge. The overlapping portions of the strips 7 are then secured together by nails, as shown in Figs. 1 and 2. The projecting portions 8 of the strips 7 are next bent inwardly or cupped, as shown at 8a. Before thus cupping the portions 8, however, the head boards 12 are placed in position, so that the cupping of the portions 110

8 secures the head boards and this fixes the barrel heads as indicated more particularly in Fig. 2. This done, the hoops 16 are slipped off and the mandrel bars 15 and reducing bands 13 are removed. If desired, additional bands 17 which may be merely wires or narrow strips of metal, can be placed around the container. This is preferably done before the mandrel bars are removed as indicated at 17 in Fig. 3.

In some instances, as shown in Fig. 5, metallic strips 18 are secured upon staves 20, in such a manner that the staves are spaced widely apart. The strips 18 are provided with portions 19, which are bent over and caused to overlap or overhang the adjacent portions of the head boards 21. These head boards are of such form that when placed together, they constitute heads, which, however, are not in this instance, circular. With the boards thus arranged, the finished container is a crate with flattened sides, as may be readily understood from Fig. 5, the staves of the crate being separated by spaces 22.

I do not limit myself to the precise form here shown for the container, nor to any particular use which may be made thereof. Generally speaking, I intend for the container to have a large variety of forms and to be used for shipping not only fruits and vegetables, but practically any other kind of merchandise which may be housed within or carried within a container.

Having thus described my invention, I claim as new and desire to secure by Letters Patent:—

1. In a device of the character described, a number of staves disposed parallel with each other, and a pair of strips secured to the end portions of the staves and projecting beyond the ends thereof, said strips be-

ing of such thickness and malleability that they are adapted to be bent in the direction of their length and in a direction lateral to their length, whereby when the staves are 45 formed into a hollow body the projecting portion of each strip serves as means for securing a head on said body.

2. A device of the character described, comprising a plurality of staves disposed substantially parallel with each other and having their ends in alinement, a pair of strips secured to said staves and projecting beyond the ends thereof, said strips being made of metal and free to be bent in the 50 general direction of their own length, said strips being of proper thickness and malleability to be bent each in a direction crossing its length, so as to occupy a plane crossing the general direction in which said staves 55 extend, and heads resting upon the staves encompassed and engaged by the projecting portions of said strips to hold them in position.

3. A container, comprising a plurality of 60 staves, metal strips secured to the staves at their ends and having portions projecting beyond the ends of the staves, and heads resting upon the ends of the staves and of less thickness than the distance the projecting portions of the strips project beyond the staves, whereby the portions of the strips beyond the heads are adapted to be bent inwardly to form a flange overlying the heads.

In witness whereof I have signed my name 70 to this specification in the presence of two subscribing witnesses.

EDWARD JACKSON YORK.
